Ill.

Filed July 18, 1960, Ser. No. 61,398

Term of patent 7 years

(Cl. D91—3)

FIG. 1 is a side elevational view of a water metering valve for lawn sprinklers showing our new design;

FIG. 2 is an end view taken from the right side of FIG. 1;

FIG. 3 is a top plan view;

FIG. 4 is an end elevational view taken from the left side of FIG. 1; and

FIG. 5 is a bottom plan view.

The side opposite that of FIG. 1 which is not shown is the mirror image of the side shown in FIG. 1.

We claim:

The ornamental design for a water metering valve for lawn sprinklers, substantially as shown and described.
